UNITED STATES PATENT OFFICE

PIERRE CLERGET, OF PARIS, FRANCE

ACTUATING MECHANISM FOR ENGINE FUEL PUMPS

Application filed January 10, 1930, Serial No. 419,991, and in France January 11, 1929.

This invention relates to the general techniques of mechanisms comprising driving members constituted by cams, receiving continuous circular movements, and driven members which must receive periodical movements.

Such mechanisms are currently applied to the valve gear of heat engines and present the following particularity:

When it is desired to impart a movement of great acceleration to a driven member, such as a tappet, for instance, the angle of engagement of the cam is limited, for a given stroke of the tappet, by the application of a wedging action of the cam against this tappet. Thus, in the case of an explosion engine operating on the four stroke cycle, and the cam of which insures the distribution of fuel must rotate at a speed one half as fast as the speed of rotation of the engine shaft, it is necessary, to obtain a lifting of the valves, which is both rapid and gives a stroke of sufficient amplitude, either to interpose amplifying mechanisms between the valve and the tappet directly engaged by the cam, or to give to the neutral surface of the cam a diameter lying within angles of engagement which does not cause wedging.

The present invention has for its object a driving mechanism by means of cams, which do not present the inconveniences above mentioned. This improved mechanism obtains, with cams of reduced dimensions, great accelerations of the driven parts at angles of engagement without causing insufficient strokes or wedging.

Such a mechanism is mainly characterized in the new combination, with at least one cam and one member to be driven, of an intermediate movable member synchronized with the movement of the cam, in such a manner that, the latter being capable of rotating as fast as desired, the movable member interposes itself between the cam and the member to be driven, at the required moment.

Such as defined by its principle, the present invention can be carried out according to various forms of construction which can differ from each other particularly by the nature of the movement adopted for the intermediate movable member arranged between the cam and the driven member, and its kinematic connection with the cam.

A particularly convenient form of construction is characterized in that the kinematic connection between the cam and the intermediate member is an epicycloidal connection, the same being capable of ensuring the actuation of several members radially arranged.

The accompanying drawing illustrates, by way of example only, a mechanism such as above characterized.

Figures 1 to 7 are diagrammatic views intended to illustrate the considerations set forth in the foregoing.

Figures 8 to 10 are detail views of a slightly modified arrangement, shown respectively in plan, in axial section and in cross section.

Figure 11 is a front view, with partial cross section, of the entire mechanism with epicycloidal connection.

Figure 12 is an axial section made according to line A—A of Fig. 11.

If α (Fig. 2) is the total angular stroke of a cam rotating at the speed of the driving shaft and β the corresponding angle for a cam having the same pitch diameter, rotating at half the speed of the driving shaft, it will be seen that the lifting of the valve in the second case, is distinctly smaller than that obtained in the first case. In both cases, the flanks of the cam are, for avoiding wedging, tangent to the cylindrical pitch surface of the cam.

The principle of the invention is illustrated in one of its forms of realization on Fig. 4. An intermediate member or slide-block 1, radially movable in a support rotating about the cam, comes, at predetermined moments,

between the cam 2 and the member to be driven. If the slide-block 1 is driven about the cam 2, in reverse direction to the rotation of the latter, the angle α expressing the angular displacement of the cam corresponding to the length of the action of the latter on the driven member, is reduced in the ratio of the angles α' and β' , α' being the real angle of engagement of the cam 2 and β' the angular displacement of the slide-block as long as it remains in contact with the cam. It will be seen that in these conditions for one and the same stroke or displacement λ of the driven member, the duration of this displacement is less and, consequently its speed greater, and conversely than with a cam in direct contact with the driven member. To this advantage, it must be added that the speed of the cam can be as high as desired, since its periods of action on the driven member are determined by the movement of the slide-block 1, and not by its real passages opposite the driven member.

The support of the slide-block or slide-blocks 1 can rotate concentrically with or eccentrically to the cam 2. In the example of Fig. 5, the support or guide 3 rotates concentrically with the cam 2, at half the speed of the latter and in reverse direction thereto. The coincidence between the cam 2 and the slide-block 1 occurs once every two revolutions. It results from this particularity that the engagement of the cam and slide-block can occur every two-thirds of a revolution and that it is thus possible to actuate three tappets arranged at 120 degrees apart. In Fig. 6, the guide 3 rotates eccentrically to the cam 2, but the principle of the operation remains the same. In Fig. 7, the guide 3 receives both a gyroscopic movement about the cam 2, and a rotation about the axis which imparts to it a gyroscopic movement. With the exception of the kinematic connection between the cam 2 and the support 3, the arrangement remains the same as that already indicated.

In the example of Figs. 8, 9 and 10, which are respectively a plan view, an axial section and a cross section of one and the same arrangement, the driven member or members or tappets 4, as well as the slide-blocks, are arranged parallel to the axis of the driving shaft 5. The support or guide 3 is in the form of a planet wheel loosely mounted on a trunnion 6 of the driving shaft 5 and rolling without sliding on internal teeth 7 concentric with the driving shaft; the cam or cams 2 are carried by an arm 8 of the driving shaft. It will be seen that it is always possible to provide a kinematic connection, between the cam or cams and the member or members to be driven for obtaining any desired positioning of the said members relatively to the cams. Moreover, by causing the angular position of the teeth 7 to vary by means of a control con-

nected to the arm 7^a, it is possible to modify the angular positions of the driving shaft for which occur the moments of engagement or of release of the driven members or tappets; in other words, advance or retardation can be obtained in the movements of actuation.

Figs. 11 and 12 illustrate a form of carrying out the invention applied to the control of fuel injection pumps on an internal combustion engine having nine cylinders radially arranged. In this form of construction, application is made of the principle diagrammatically shown in Fig. 1, and which comprises a single cam 2, a rotary guide 3, with multiple slide-blocks 1, rotating concentrically with or eccentrically to the driving shaft, in order to ensure the periodical actuation of tappets 4 radially arranged.

In this example of construction, it is necessary to successively actuate nine injection pumps for nine cylinders, the phases of which occur every eighty degrees of rotation of the driving shaft.

The driving shaft 5 is provided with a double helical incline on which is fitted a cam 2 provided with a double annular flange 10 forming a groove for one or more rollers arranged at the end of a lever 11, or of a fork pivoted on an axis 12 of the fixed frame of the engine which allows, by means of any suitable operating rigging, of modifying the position of the cam on the shaft 5.

The guide or support for the slide-block 3 is coaxially arranged to the shaft 5; it is centered on the latter and can be made of several sections suitably connected, for allowing the assemblage of the cam. It is provided with four guide slides for four radial slide-blocks 1 spaced 90 degrees apart and which move in the plane common to nine tappets returned in the centripetal direction by springs 13 and attached, through rods 14, to the pumps to be actuated (not shown in the drawing). The tappets 4 are guided in radial bearing portions of the fixed frame of the engine and are provided with tops or abutments 15 for limiting their centripetal displacements.

The guide 3 is provided with a plate 3^a on which are formed internal teeth 16 constantly gearing with a pinion journaled on an axis 18 of a plate 19 loosely mounted on the driving shaft 5, and connected, by an arm 20, to an operating rigging (not shown in the drawing). The pinion 17 is driven by a pinion 21 rigidly mounted on the driving shaft and constantly gearing with a pinion 17^a angularly connected to the first pinion 17. The set of gears thus obtained is such that the guide 3 rotates in reverse direction to the cam 2 and at a speed equal to $1/8$ of that of the driving shaft 5. Fixed cams or inclines 22 are provided for returning the slide-blocks 1 in the centripetal direction, so as to avoid any

prejudicious shocks on the heel portions 4^a of the tappets 4. These arcuate heel portions are adapted to allow a displacement of the slide-blocks relatively to the tappets, without the latter ceasing to be actuated by the said slide-blocks at the required moments, between limits determined by the circumferential extent of the heel portions 4^a.

It is to be noted that the device thus constructed effects two distinct adjustments. A first adjustment is obtained by the lever 11, and a second adjustment by the arm 20. If the two possible adjustments are in the same direction, they are added to each other; they are subtracted from each other if they are of reverse directions. The plate can carry cams 23 for the control of other tappets 24, in view of obtaining any desired result.

The pinion 21 can also be acted upon by any suitable mechanism for the purpose of displacing it relatively to the shaft 5 and to add an adjusting element to those already mentioned.

It is to be noted that the inclines 22, the function of which has been indicated above, can, if necessary, be angularly displaced at the same time as the slide-block 1. For that purpose, the inclines are formed on a crown 22^a, provided with an operating lever 22^b, independent, or kinematically connected, by any suitable mechanism, to any of the arrangements which permit the modification of the position of the slide-blocks relatively to the cam.

The mechanism which has just been described is a simple example of carrying out the invention. The latter is defined by the features set forth in the present specification, and, whatever may be the applications of the same, it includes in its scope, all the means and combinations of means suited to the carrying into practice of these features, for the purpose of obtaining the industrial result set forth.

What I claim as my invention and desire to secure by Letters Patent is:—

1. Mechanism for periodically actuating fuel pumps on internal combustion engines including in combination a driving cam, a driven member, an intermediate movable member coacting with the cam and driven member, and means for moving the intermediate member synchronously with respect to the operation of the cam so that the intermediate member will be interposed between the cam and driven member and actuated by the cam, said moving means including a rotating support in which the intermediate member is mounted for radial sliding movement.

2. Mechanism as claimed in claim 1, wherein the support for the intermediate member moves in a direction opposite to the direction of rotation of the driving cam.

3. Mechanism for actuating fuel pumps

on engines with radially arranged pistons, including in combination a driving shaft, a cam thereon, slide blocks between the cam and pistons, and a guide in which the slide blocks are mounted for radial sliding movement mounted to rotate about the driving shaft and in an opposite direction to the rotation thereof.

In testimony whereof I have signed this specification.

PIERRE CLERGET.
